UNITED STATES PATENT OFFICE.

LOUIS DUNKELSBERG, OF NEW YORK, N. Y.

DESIGN FOR AN EYEGLASS FRAME.

Application filed June 27, 1927. Serial No. 22,569. Term of patent 7 years.

To all whom it may concern:

Be it known that I, LOUIS DUNKELSBERG, a citizen of the United States of America, residing in the city of New York, county of Kings, and State of New York, have invented a new, original, and ornamental Design for Eyeglass Frames, of which the following is a specification, reference being had to the accompanying drawings, forming part thereof.

Fig. 1 is a front elevation of an eyeglass frame embodying the invention; and

Fig. 2 is a middle transverse section thereof on line 2—2 of Fig. 1.

I claim:

The ornamental design for an eye glass frame as shown.

In witness whereof I have signed this specification this 25th day of June, 1927.

LOUIS DUNKELSBERG.
